COLLAR CLIP

William E. De Laney, Willow Grove, Pa.

Application September 21, 1938, Serial No. 230,951

3 Claims. (Cl. 24—81)

My invention relates to new and useful improvements in a collar clip of the type used for holding the ends or flaps of collars, especially soft and semi-stiff ones, in proper positions relative to each other and to other articles of the user's wearing apparel in order to maintain a neat appearance.

One of the objects of the present invention is to produce a relatively inexpensive device of this character which is durable and efficient in operation and which accomplishes certain purposes in a unique and novel manner.

Another object of the invention is to provide a collar clip in which the clasps are universally movable relative to each other and the several elements are capable of changes in positions with relation to one another whereby said collar clip will remain in place on the collar even though the latter is temporarily disarranged due to movements of the throat or neck muscles, especially abnormal movements, as when a person coughs.

Another object of the invention is to provide a collar clip consisting of a spring and clasps pivotally connected with ends of said spring to permit of universal movements.

Another object of the invention is to provide means for limiting the extensibility of the spring.

A further object of the invention is to provide a housing for the spring which will not interfere with movements of the parts of the collar clip.

A still further object of this invention is to utilize the properties of a contractile spring for accomplishing the same purposes as when using an extensile spring.

With the above and other objects in view, this invention consists of the details of construction and combination of elements hereinafter set forth and then designated by the claims.

In order that those skilled in the art to which this invention appertains may understand how to make and use the same, I will describe its construction in detail, referring by numerals to the accompanying drawing, in which—

Fig. 1 is a view of a collar illustrating the manner of use of the collar clip.

Fig. 2 is a front elevation of the collar clip illustrating the parts in a straight line position and showing in dotted lines several of the locations which can be assumed by the clasps relative to each other and to the spring for giving the universal movements.

Fig. 3 is a plan view of the collar clip shown in Fig. 2 and also illustrating in dotted lines some

of the positions which the clasps are capable of assuming.

Fig. 4 is a plan view of the collar clasp with the addition of means to limit the extension of the spring, the latter being shown in section and contracted.

Fig. 5 is a similar view of the same device illustrating the spring in its fullest permissible extended condition.

10 Fig. 6 is a plan view of a modification wherein the spring is housed within a casing that limits the extensibility of said spring and in which the device is shown contracted.

Fig. 7 is a view illustrating the device of Fig. 6 contracted.

15 Fig. 8 is a sectional plan view of another modification wherein a contractile spring is used, the collar clip being illustrated as in a contracted condition.

20 Fig. 9 is a view of the device in Fig. 8 illustrated in an extended or expanded condition.

Fig. 10 is a section on the line 10—10 of Fig. 9.

25 In carrying out my invention as herein embodied, particular reference being first had to Figs. 1 to 5 inclusive, 15 represents a spring of the extensile type having an eye 16, or equivalent attaching means, at each end. To each eye 16 is pivotally or swingingly connected a spring clasp 17 so that said clasps may move about in all directions or assume any positions relative to each other and to the spring as suggested by the dotted lines in Figs. 2 and 3. These universal movements permit a user to apply the collar clip to the ends or flaps of a collar in any desired position and permit said collar clip to yield with the usual movements of the wearer and also allows changes in positions of the parts when abnormal movements of the neck and throat muscles take place.

30 40 In actual practice, the clasps are attached to the opposite ends or flap of a collar and the spring will provide sufficient tension to hold the collar snug, neat appearing and in proper position about the neck of the wearer and still allows freedom of movements without disengaging either end of the collar clasp from the collar which so often happens in connection with ordinary unyielding clips, clasps or pins and which is exceedingly distressing and annoying to the wearer.

45 50 In addition to the universal movements of the clasps 17 on the spring 15, said spring is also capable of flexion thus making the collar clip, as a whole, readily yieldable to outside influences

while, at all times, urging the collar ends to the desired positions.

While the clasps 17 may be of any suitable construction to grip the collar ends, the ones shown for purposes of illustration are produced from spring material and each is fashioned to provide coating jaws 18 and 19 with an entrance or mouth 20 between them whereby they may be attached to the eyes of the spring during the course of manufacture and slipped over the edges of the collar ends when the collar clip is to be used.

As will be obvious by reference to Fig. 5, the spring 15 can be and is extended or expanded when the collar clip is being attached to the collar ends and at any time while in use when certain parts of the wearer's body are moved and in order to prevent undue extension or expansion of said spring beyond its critical point, a flexible suppressor means 21, such as a chain or any equivalent thereof, for instance a string, cable or the like, has its ends attached to the clasps and extends through or around the spring 15. This allows the spring 15 to contract without interference but limits its expansion so that tension thereof will not be weakened or otherwise damaged.

In Figs. 6 and 7 I have illustrated the same general principle except that the suppressor takes the form of a flexible casing or housing 22 capable of being extended and shortened. This casing is produced from suitable material in ribbon form, woven or pleated into a tubular structure and preferably but not essentially closed at both ends. The casing embraces or surrounds the spring 15 so as to substantially enclose the latter and the ends of said casing are connected or linked to the clasps 17 by loops 22a. Because of the formation of said casing, the movements of the spring in any direction are not interfered with, except for the limitation placed upon the extensibility or expansibility thereof. When this last described form of the invention is being used, the spring 15 and the suppressor-casing 22 are extended in unison, as shown in Fig. 7, by the opposite force applied to the clasps 17 but when said clasps are released the spring 15 will contract and draw the ends of the suppressor-casing towards each other, thus shortening the latter so as to approximately correspond to the contracted body length of said spring as illustrated in Fig. 6.

The modification depicted in Figs. 8, 9 and 10

comprises two hollow telescoping members 23 and 24 constituting a casing which houses the contractile spring 25. The member 24, in reality, contains said spring at all times and has an abutment 26 at its inner end, preferably formed by bending portions inward. The member 23 also has an abutment 27 at its inner end which, like abutment 26, preferably is formed by bending in sections of the casing and these sections project through and slide in longitudinal slots 28 in the member 24. The spring 25 is positioned within the member 24, as before stated, and has its opposite ends engaging the abutments 26 and 27 to urge them apart and thus contract the casing. The outer ends of the casing members carry eyes 29 or equivalent means for pivotally or swingingly connecting the spring clasps 30 to opposite ends of the casing whereby said clasps are universally movable relative to each other and to the casing. By this particular arrangement, when the spring 25 is free to expand the casing of the collar clip is shortened as shown in Fig. 8, but when said collar clip is caused to yield or be extended the spring will be compressed as illustrated in Fig. 9.

It is to be particularly noted that a collar clip constructed as above described, is exceedingly flexible and capable of yielding to any movements of a person's body, either voluntary or involuntary and therefore is unlikely to become detached from a collar which can and does happen with those of rigid form even though they embody the feature of extensibility.

Of course, I do not wish to be limited to the exact details of construction herein shown and described, as these may be varied within the scope of the appended claims without departing from the spirit of my invention.

Having thus described my invention, what I claim as new and useful is:

1. A collar clip comprising a pair of collar engaging elements, an extensile spring having each end connected to an element in a manner to permit the latter to move in any direction, and suppressor-casing enclosing the spring and linked to the collar engaging elements.
2. The structure in claim 1 wherein the suppressor-casing is a flexible structure capable of extending and retracting.
3. The structure in claim 1 wherein the suppressor-casing is a hollow tubular member of woven ribbon strands.

WILLIAM E. DE LANEY.
